PAPERWEIGHT OR SIMILAR ARTICLE

Hazel Jacks, 5520 Sabine Drive,
Marrero, La. 70072

Filed July 6, 1973, Ser. No. 377,134

Term of patent 14 years

Int. Cl. D19—02

U.S. Cl. D19—97

FIG. 1 is a perspective view of a paperweight or similar article showing my new design;

FIG. 2 is a top plan view;

FIG. 3 is a left side elevational view;

FIG. 4 is a bottom plan view;

FIG. 5 is a rear elevational view; and

FIG. 6 is a front elevational view.

I claim:

The ornamental design for a paperweight or similar article, as shown and described.
